UNITED STATES PATENT OFFICE.

HANS G. JORGENSEN, OF ERIE, PENNSYLVANIA.

ASH RECEPTACLE.

Application filed May 25, 1923. Serial No. 641,375.

This invention is designed to form a convenient ash receptacle that can be readily mounted in such positions as an automobile dash. The invention includes as a feature a cigar cutter which discharges to the receptacle.

The invention is illustrated in the accompanying drawings as follows:

Fig. 1 shows a central section through a receptacle in place on a dash.

Fig. 2 a section on the line 2—2 in Fig. 1.

Fig. 3 a section on the line 3—3 in Fig. 1.

Fig. 4 a section on the line 4—4 in Fig. 1.

1 marks the automobile dash, 2 an opening therethrough, and 3 a cylindrical mounting for the receptacle, this mounting being screw-threaded at 4 having a shoulder forming a face on the inner surface of the dash. A nut 6 is screwed on to the screw-threaded portion, clamping the mounting on the dash.

20 A drawer 7 of cylindrical form is slidably mounted in the member 3 and is closed at its inner end by a plate 8 and at its outer end by a cover 9 which is spun over the end 25 of the cylindrical tube forming the drawer. An opening 10 is cut in the upper face of the receptacle to permit of the depositing of ash in the receptacle when the receptacle is drawn out. The mounting has a depression, or key 11 at its inner end which is 30 adapted to fit in a slot 12 in the receptacle so as to maintain it in its proper position when moved into place.

The cover has a cylindrical projection 13. 35 A knob 14 has a cylindrical projection 15 extending through the projection 13 and the projection 15 is headed over on the inside of the shoulder. The projection 15 is rotatable in the projection 13 and a perforation 17 is 40 arranged in the projection 13 adapted to come into register with a perforation 18 in the projection 15. The perforation 18 has

cutting edges so that if a cigar is placed through the perforations 17 and 18 and the knob 14 turned the end of the cigar is 45 clipped, discharging into the receptacle 7. By forming the mounting and parts of cylindrical shape they can be readily mounted in the dash by forming a circular opening therein and the mounting can be provided with a 50 screw thread by means of which the mounting is readily clamped in place.

What I claim as new is:

1. In an ash receptacle, the combination of a cylindrically shaped mounting, said mounting being screw-threaded at one end and provided with a shoulder; a clamping nut on the screw thread; and a cylindrical drawer slidably mounted therein.

2. In an ash receptacle, the combination of a cylindrically shaped mounting, said mounting being screw-threaded at one end and provided with a shoulder; a clamping nut on the screw thread; and a cylindrical drawer slidably mounted therein, said drawer being in the form of a tube with a slot at its upper face, the tube being closed at its ends, one end forming a cover for the drawer.

3. In an ash receptacle, the combination of a cylindrical mounting having a screw thread at one end and a shoulder; a clamping nut on the screw thread; a depression in the end of the cylindrical portion forming a key; and a cylindrical drawer sliding in the mounting and having a key-way cooperating with the depression for locking the drawer in an upright position, said drawer being in the form of a tube with an opening in its top.

In testimony whereof I have unto set my hand.

HANS G. JORGENSEN.
